UNITED STATES PATENT OFFICE

JOSEPH A. RAYDER, OF PHILADELPHIA, PENNSYLVANIA

SOUND-AMPLIFYING DEVICE

Application filed December 13, 1928. Serial No. 325,815.

This invention relates to devices useful for amplifying sounds such as stethoscopes, devices for location of leakages, for locating engine knocks and analogous instruments 5 useful in the scientific or mechanical arts for tracing sounds to their source of origin.

Primarily I aim to provide an instrument of the stated character that is exceptionally sensitive in its amplification, of novel construction, cheap to manufacture; or, in other words, one which when once adjusted is sealed against tampering.

Another aim is the provision of a device of the typified nature which is readily adapted for use in the mechanical arts or the medical profession.

With the foregoing aims or objects in view my invention essentially comprises a hollow body having an interfitted diaphragm characterized by a contact pin with which is adapted to co-operate with a vibratory element of highly sensitive type, said body being provided with interchangeable pins or probes whereby the device is rendered capable of diversified use.

In the following description reference is made to the accompanying sheet of explanatory drawings, which fully set forth the nature and character of the improvements involved, and in the claims appended hereunto I point out and clearly define the alleged novel features.

In the views:

Fig. 1 is a broken and in part axial sectional view of my improved sound amplifying device or stethoscope.

Fig. 2 is a section on the plane indicated by the arrowed line 2—2 in Fig. 1.

Fig. 3 is a similar sectional view on the plane designated 3—3 in Fig. 1; and,

Fig. 4 is a detail view of an alternative type of pin or probe hereinafter fully explained.

Referring more in detail to the drawings my novel sound amplifying device comprises 45 substantially counterpart cup-shaped elements 5, 6 adapted for opposed connection by means of a common interfitting sleeve or union 7. For convenience in assemblage the bores of the respective cup-shaped elements 50 5, 6 are screw-threaded for engagement by

the correspondingly threaded exterior wall of the union 7, as indicated by the numeral 8.

The cup-shaped element 5, it will be seen, is provided with a co-axial tubular shank 9 that is conveniently reduced at 10 for reception of the customary tubing 11 connecting with the aural fork 12—a fragment only of which is shown for convenience in illustration—in accordance with common practice.

Seating in the cup-shaped element 5, through the medium of a peripherally-embracing longitudinally-split resilient tube 13 of fine bore is the diaphragm 14. It is to be particularly noted that the length of resilient tube 13 has its ends brought together in close proximity at 13', Fig. 2, and that it is of a cross-section to support the diaphragm 14 concentric of the bore of the cup-shaped element 5; and that said diaphragm and tube are secured in place by the sleeve or union 7, in an obvious manner.

Centrally of the diaphragm 14 I fit a pin 15 that is conveniently screw-threaded to receive a lock nut 16, and which is fashioned to a needle point at 17, for a purpose later on explained.

Referring now to the cup-shaped element 6, it will be seen, the same is provided with a tubular shank 18, into the inner end of which is threaded a screw 19 that serves to secure a highly sensitive spring tongue or vibrator 20 in place with interposition of a spacer or washer 21. The tongue or vibrator 20 preferably consists of a thin flat strip of inherently springy metal that is retroverted to approximately U-shape—as best shown in Fig. 1; while it is to be particularly remarked that it is of a dimension across the paralleling legs so as not to normally contact with the apex of the needle point 17, but susceptible of transferring the most sensitive sound vibrations to said point when its quiescence is disturbed.

Fitting the outer end of the tubular shank 18 of the cup-shaped element 6 is a removable shouldered contact pin or probe 22 which may be of any desired length, provided it is rigidly connected in place. This pin or probe 22 provides a means for reaching into normally inaccessible places; or for probing the

ground when searching for pipe or main leaks. When the device is to be used for ordinary stethoscopic purposes as when examining the human body, I remove the probe 22, and substitute therefor the pin 23, shown in Fig. 4; said pin being fitted with a hard rubber button or head 24 so as to eliminate metallic contact with the skin as well as adapting the device for easy manipulation without inflicting annoyance to sensitive persons.

It is further noteworthy that both of the cup-shaped elements 5, 6 are respectively dished at 25, 26, and that the surrounding outer walls are concaved at 27 so as to ensure a firmer grasp being obtainable when manipulating the device; and finally that when the component parts are adjusted and assembled as shown, the joint between the elements 5, 6 is hermetically sealed, whereby the device is rendered proof against tampering or disturbance of its sensitivity.

From the foregoing it is thought the inherent simplicity and advantages of my novel sound amplifying device or stethoscope will be apparent, while I reserve the right to make such detail changes as are reasonably encompassed by liberal interpretation accorded the following claims.

Having thus described my invention, I claim:

1. In a sound amplifying device the combination of counterpart opposedly connected cupped elements, one of which houses a diaphragm with a co-axial needle and the other a cooperative inherently springy vibrator.

2. In a sound amplifying device the combination of counterpart opposedly connected cupped elements, one of said elements housing a diaphragm with an attached co-axial needle, the other of said elements having a highly sensitive strip vibrator attached thereto with capacity to communicate sound vibrations to the point of the needle aforesaid.

3. In a sound amplifying device the combination of counterpart opposedly connected cupped elements, one of said elements housing a diaphragm with an attached co-axial needle, and a U-shaped springy strip secured in the other of said elements with one of its paralleling legs adapted for vibratory co-operation with the point of the needle aforesaid.

4. In a sound amplifying device the combination of counterpart opposedly connected cupped elements, one of said elements housing a diaphragm with an attached co-axial needle, a U-shaped inherently springy strip secured by one of its paralleling legs in the other cupped element and its free leg adapted for vibratory contact with the point of the needle aforesaid, and a removable contact exterior of said last mentioned element.

5. In a sound amplifying device the combination of counterpart opposedly connected cupped elements, one of said elements hous-

ing a diaphragm with an attached co-axial needle, a U-shaped inherently springy strip secured by one of its paralleling legs with interposition of a spacing washer in the other cupped element and its free leg adapted for vibratory contact with the point of the needle aforesaid, and a removable contact exterior of said last mentioned element.

6. In a sound amplifying device the combination of counterpart cup-shaped elements each of which has a concentric tubular shank, an interfitting union serving to couple said elements rigidly together, a diaphragm with a co-axial pin seating in one of the aforesaid elements by aid of a peripherally engaging resilient split tube, a U-shaped inherently springy strip secured by one leg with interposition of a spacer in the other cup-shaped element, said U-shaped strip having its free leg adapted for vibratory contact with the point of the diaphragm pin, and a removable contact probe engaged in the tubular shank of the last mentioned element.

7. In a sound amplifying device the combination of counterpart cup-shaped elements each of which has a concentric tubular shank, an interfitting union serving to couple said elements rigidly together, a diaphragm with a co-axial pin seating in one of the aforesaid elements by aid of a peripherally engaging resilient split tube, a U-shaped inherently springy strip vibrator secured by a screw and interposed spacer to the inner end of the opposed cup-shaped element tubular shank, the free leg of the strip vibratory serving to transmit sound waves to the diaphragm pin, and a removable contact probe with a button end engaged in the outer end of the tubular shank aforesaid.

In testimony whereof I affix my signature at Philadelphia, Pa., this 16th day of November 1928.

JOSEPH A. RAYDER.
